UNITED STATES PATENT OFFICE.

AARON P. STORRS, OF OWEGO, NEW YORK, ASSIGNOR TO STORRS MICA COMPANY, OF OWEGO, NEW YORK, A CORPORATION OF NEW YORK.

MICA CYLINDER FOR INVERTED GAS-MANTLES.

1,081,343.

Specification of Letters Patent. Patented Dec. 16, 1913.

Application filed December 21, 1912. Serial No. 737,924.

To all whom it may concern:

Be it known that I, AARON P. STORRS, a citizen of the United States, a resident of Owego, Tioga county, State of New York, have invented a certain new and useful Mica Cylinder for Inverted Gas-Mantles, of which the following is a specification.

This invention relates to cylinders of mica for use with inverted gas burners, utilizing an incandescent mantle.

In my Patent No. 1,027,449, dated May 28, 1912, I show such a cylinder, with a mica bottom, and with openings in the sides for the entrance of air to support combustion.

The present invention has for its object the production of a cylinder with means to prevent the fall of carbon, or broken portions of the mantle or mantle ring, which will not obstruct the light, which will be extremely durable, cheap to construct, and will keep out insects. These and further objects will appear from the following description and accompanying drawings, considered together or separately.

In the drawings, Figure 1 is a longitudinal sectional view of a cylinder embodying the invention, showing the mantle and mantle ring; Fig. 2 is a transverse section taken on the line 2—2 of Fig. 1, looking in the direction of the arrow; and Figs. 3 and 4 are views of details.

In all the views like parts are designated by the same reference characters.

The mica cylinder 1 is preferably made of the shape shown. It is also conveniently made of a plurality of sheets of mica, due to commercial conditions, under which single sheets of sufficient size to make a cylinder are difficult to obtain. These sheets are overlapped as shown, at the joints, and secured together by means of eyelets 2, which form a convenient means of connection, and also afford a means for entrance of air. The top of the cylinder has the usual band 3, attached in any suitable manner. This band is connected to the mantle ring 4, by any suitable means, those illustrated, which form no part of the present invention, being similar to those disclosed in my pending application for patent, filed May 23, 1912, Serial No. 699,111. It is to be understood that any suitable means may be employed for supporting the cylinder from the mantle ring, those shown being solely

for the purposes of illustration. Within the cylinder is the usual incandescent mantle 5.

The bottom of the cylinder 1, is provided with a metallic, annular nosing 6. This may conveniently be made of tin. It is preferably made as shown, the metal being doubled upon itself to form a gutter 7, which pinches the lower edge of the mica sheets and securely holds the nosing in place. The ends of the nosing are joined by overlapping at 8. This joint may conveniently be made adjacent to one of the joints of the mica sheets as shown, which reduces the cost, as the nosing before the ends are joined may be attached to the mica, and the ends connected by the same operation which joins the overlapping ends of the mica. To assist in securing the nosing in place the lowermost eyelet 2^a may also engage with the nosing as shown. Below the gutter 7 the nosing is made in the shape of an annular flange 9, for supporting the bottom 10.

The bottom is made of gauze, preferably of metal woven wires. This bottom is circular in outline, and snugly fits within the nosing, resting upon and being supported by the flange. The size of aperture of the gauze is immaterial, provided that it is not so fine that it will exclude light, nor so coarse that it will not properly intercept falling pieces of carbon, or fragments of the mantle or ring. It should be sufficiently fine to properly exclude insects, and at the same time admit air to support combustion. The thickness of the wire should be sufficient to prevent the gauze from being broken by handling, and to support pieces of carbon or mantle, or portions of or the whole of the mantle ring, in the event that the latter drops.

A very important feature of the invention lies in making the bottom of such a shape that it is distorted beyond the plane of its periphery, in the direction toward the mantle. In the embodiment chosen for illustration, it is dome-shaped, as shown. This greatly adds to its strength. It also adds to the security of connection of the gauze within the cylinder. Before the gauze can be ejected it must first become flattened, and the distorted shape resists flattening. A further advantage is that the gauze is not readily expelled from the cylinder. This is because the nosing is of fixed diameter;

in other words, is incapable of expansion, while the gauze, in order to be flattened, must necessarily increase in diameter, a condition which is resisted by the nosing. 5 Therefore, even if the comparatively heavy mantle ring drops upon the gauze, it will, under no circumstances, distort the bottom beyond the plane of its periphery in the direction away from the mantle, and thus 10 drive it out of the cylinder, and consequently no hot or incandescent substances can fall out of the cylinder. Another advantage resides in the fact that, in use, the bottom requires absolutely no fastening 15 means but is securely held in position by simply resting on the flange. In order to assist in holding the bottom in position, while handled, and to prevent it being forced upward, I provide lips 11, at intervals around the flange 9, such lips being conveniently made by two slits close together, and bending the material of the flange between the slits, upward, as shown. The ends of one or two of the wires, which constitute 20 the gauze, may be bent outward and made to rest beneath these lips, as shown, so that they will produce a locking means to prevent the gauze from being lifted from the flange. 25 I make no claim in this application to the means for supporting the cylinder by the mantle ring, such means being specifically described and claimed in my co-pending application for patent, above identified. 30 In accordance with the provisions of the patent statutes, I have described the principle of my invention, together with the apparatus which I now consider to represent the best embodiment thereof; but I desire to 35 have it understood that the apparatus shown is merely illustrative, and that the invention may be carried out in other ways.

Having now described my invention, what I claim as new and desire to secure by Letters Patent, is:—

45

1. A cylinder for inverted incandescent burners, having walls of mica, a bottom of gauze, distorted inwardly beyond the plane of its periphery, in the direction toward the mantle, and means for preventing the perimeter of the gauze from increasing.

50

2. A cylinder for inverted incandescent burners, having walls of mica, with a metal annular nosing at the bottom, said nosing having a flange, and a circular gauze bottom, distorted inwardly beyond the plane of its periphery, in the direction toward the mantle; resting upon the flange and bearing against the nosing.

55

3. A cylinder for inverted incandescent burners, comprising a body of mica, a metal nosing at the bottom with a gutter grasping the mica, and an annular flange, with a lip or lips therein, and a bottom of wire gauze, convex in shape, resting upon the flange, and abutting against the nosing, with a wire or wires below each lip, for retaining the gauze in position.

60

4. A cylinder for inverted incandescent burners, having walls of mica, a metal annular nosing at the bottom thereof inclosing the edge of the mica and having an inwardly extending flange, a circular gauze bottom distorted inwardly beyond the plane of its periphery, in the direction toward the mantle, resting on the flange and bearing against the nosing.

70

This specification signed and witnessed this 20th day of December, 1912.
